UNITED STATES PATENT OFFICE.

WALTER H. GREEN, OF CHICAGO, ILLINOIS, ASSIGNOR TO KENNICOTT
WATER-SOFTENER COMPANY, OF CHICAGO, ILLINOIS, A CORPORATION
OF ILLINOIS.

WATER-PURIFIER.

SPECIFICATION forming part of Letters Patent No. 767,746, dated August 16, 1904.

Application filed April 15, 1904. Serial No. 203,324. (No model.)

To all whom it may concern:

Be it known that I, WALTER H. GREEN, a citizen of the United States, residing at Chicago, in the county of Cook and State of Illinois, have 5 invented a new and useful Improvement in Water-Purifiers, of which the following is a specification.

My invention relates to the means employed in water-purifying apparatus for automatically supplying the chemical solution in predetermined proportion to the water to be treated for "softening" or purifying the water, thereby better to adapt it for industrial purposes; and it relates particularly to an improvement upon the apparatus for the purpose stated set forth in United States Letters Patent No. 732,357, dated June 30, 1903, to Cass L. Kennicott.

My object is to provide an improved construction of the mechanism actuated by the tilting receptacle to feed to it the predetermined proportion of the chemical solution from the holder thereof, thereby, particularly, with reference to the device of the aforesaid 25 patent, to increase the capacity of the holder and to simplify its construction and operation.

In the accompanying drawings, Figure 1 shows my improved apparatus in front elevation with parts represented by dotted lines, and Fig. 2 is a section taken at the line 2 on 30 Fig. 1 and viewed in the direction of the arrow.

A is the tank or holder for the chemical solution, shown of general cylindrical shape, and it is usually connected for supplying it with 35 a chemical-mixing tank (not shown) such as is commonly provided in apparatus of the class to which my improvement relates. Adjacent to the base of the holder is journaled on a suitable support *a* to rock on its center the tilting receptacle B of the preferred scoop form illustrated, with a central vertical partition *b* within it, dividing it into compartments *c* and *c'*. The water to be treated enters the receptacle B from a valved supply-pipe C.

40 A rope *d*, chain, or other suitable flexible medium is fastened at its ends to the opposite ends of the receptacle B, passing therefrom over two sets of pulleys *e e* and *e' e'*, journaled on sup-

ports *f* on the upper end of the holder A, and down into the latter between the pulley sets 50 about a guide-sheave *g*, journaled in the holder near its base. On the rope *d*, within the chemical-solution holder and preferably on each length thereof, as shown, is flexibly fastened a cup *h*, the capacity of which should be suitably 55 proportioned to that of each compartment in the tilting receptacle to be filled by lowering it from the contents of the holder A and discharged when raised over the upper edge of the latter into a hopper *i*, from which a pipe *k* leads 60 downward to the receptacle B. Guides are provided, one for each cup, in its movements, that shown in Fig. 2 comprising a pair of parallel longitudinally-slotted bars *l*, fastened in proper position to the inner surface of the 65 wall of the holder to extend vertically therein and beyond its upper edge, over which each bar is arched toward the hopper. The cup is hinged at its lower edge to the rope and has lateral studs confined in the slots of its guide-bars *l*, whereby as the filled cup is raised to the position of that shown in Fig. 2 and by the full lines in Fig. 1 it is turned to empty 70 its contents into the hopper *i*. A shield *n* is provided for each cup to extend over it, being 75 supported for that purpose in the tank on the rope *d* therein. This shield tends to prevent, in settlement of the solution in the tank, the deposit of particles in suspension into the cup, which would unduly increase the strength of 80 its contents, and during the period that the apparatus is out of operation the shield prevents such a deposit in the cup as would tend to clog it therewith. As the water to be treated flows into the receptacle B from the 85 pipe C it fills the compartments of the receptacle alternately, thereby rocking it and discharging into a tank (not shown) for the water undergoing treatment the one compartment while the other is filling. This rocking motion of the receptacle actuates the rope *d* alternately to lower and raise the cups *h h*, 90 whereby the contents of each are introduced into the respective compartments of the tilting receptacle before they become filled with 95 the water to be treated.

The gist of my improvement consists in so connecting with the tilting receptacle the cup or cups as to adapt the latter to be moved vertically in the chemical-solution tank. This 5 enables me to increase the capacity of the solution-tank over that of the aforesaid patent, since it permits the base of the tank to be flat instead of rounded, and the construction is much simpler and materially cheaper to produce than that of the patented apparatus, because of the regular form permissible for the solution-tank, of the omission of the conduits for conducting the solution to the tilting receptacle, and of the rock-shaft and link connections 10 between the holder and receptacle, while the friction due to those connections and that of the cups against the sides of the holder is dispensed with, thus enabling the apparatus to run more easily.

20 While the means shown and described for embodying the aforesaid gist of my improvement are thoroughly practicable and desirable, it may be embodied in other forms. Hence I do not limit my invention to the particular form of its embodiment herein set forth.

25 What I claim as new, and desire to secure by Letters Patent, is—

1. The combination with a chemical-solution holder of a water-purifying apparatus, 30 of a tilting receptacle supported to be rocked by the weight of the water to be treated flowing into it, cup raising and lowering mechanism connected with said receptacle to be actuated by its movement, and a cup supported in said holder by said mechanism to be thereby vertically raised bodily above the liquid-level in the holder and lowered therein.

2. The combination with a chemical-solution holder of a water-purifying apparatus, 40 of a tilting receptacle supported to be rocked by the weight of the water to be treated flowing into it, cup raising and lowering mechanism connected with said receptacle to be actuated by its movement, a cup supported in said holder by said mechanism to be thereby vertically raised and lowered therein, and a guide for the cup in its movements operating to hold it in upright position and to turn it for its discharge at the upper end of said holder.

50 3. The combination with a chemical-solution holder of a water-purifying apparatus, of a tilting receptacle supported to be rocked by the weight of water flowing into it, a cup suspended in said holder and a flexible connection between said receptacle and cup upon which the cup is suspended to be vertically raised bodily above the liquid-level in the holder and lowered therein by the movement of said receptacle.

60 4. The combination with a chemical-solution holder of a water-purifying apparatus, of a tilting receptacle supported adjacent to said holder to be rocked by the weight of water flowing into it, a rope, or the like, fas-

tened to said receptacle and guided into said tank to be actuated by the movements of the receptacle, and a cup supported in the tank on said rope to be vertically raised bodily above the liquid-level in the holder and lowered therein by the movements of said receptacle, 70 substantially as and for the purpose set forth.

5. The combination with a chemical-solution holder of a water-purifying apparatus, of a tilting receptacle supported adjacent to said holder to be rocked by the water flowing 75 into it, a rope, or the like, fastened to said receptacle and passing between its ends over guide-pulleys into said tank to be actuated by the movements of the receptacle, a cup supported in the tank on said rope to be vertically raised bodily above the liquid-level in the holder and lowered therein by the movements of said receptacle, and a guide for the cup in its movements, substantially as and for the purpose set forth.

6. The combination with a chemical-solution holder of a water-purifying apparatus, of a tilting receptacle supported adjacent to said holder to be rocked by the weight of water flowing into it and divided into compartments, a rope, or the like, fastened at its ends to the ends of said receptacle and passing thence over guide-pulleys downward into said tank and about a guide-sheave journaled therein, a pipe discharging into said receptacle, 90 and one or more cups supported in the tank on said rope to be actuated by its movements to discharge into said pipe, substantially as and for the purpose set forth.

7. The combination with a chemical-solution holder of a water-purifying apparatus, of a tilting receptacle supported adjacent to said holder to be rocked by the weight of water flowing into it and divided into compartments, a rope, or the like, fastened at its 105 ends to the ends of said receptacle and passing thence over guide-pulleys downward into said tank and about a guide-sheave journaled therein, a hopper having a pipe discharging into said receptacle, and cups supported in the tank on said rope to be actuated by its movements to discharge alternately into said hopper, substantially as and for the purpose set forth.

8. The combination with a chemical-solution holder of a water-purifying apparatus, of a tilting receptacle supported adjacent to said holder to be rocked by the weight of water flowing into it and divided into compartments, a rope, or the like, fastened at its 110 ends to the ends of said receptacle and passing thence over guide-pulleys downward into said tank and about a guide-sheave journaled therein, a hopper having a pipe discharging into said receptacle, cups supported in the tank on said rope to be actuated by its movements to discharge alternately into said hopper, and guides in the tank for said cups di-

recting them to their points of discharge into the hopper, substantially as and for the purpose set forth.

9. The combination with a chemical-solution holder of a water-purifying apparatus, of a tilting receptacle supported adjacent to said holder to be rocked by the weight of the water flowing into it and divided into compartments, a rope, or the like, fastened at its ends to the ends of said receptacle and passing thence over guide-pulleys downward into said tank and about a guide-sheave journaled therein, a hopper having a pipe discharging into said receptacle, cups hinged in the tank 15 on said rope to be actuated by its movements to discharge alternately into said hopper, and having guide-studs extending from them, and

slotted bars extending in the tank and curved over the edge of the latter toward said hopper with said studs movably confined in their slots, and affording guides for the cups, substantially as and for the purpose set forth.

10. The combination with a chemical-solution holder of a water-purifying apparatus, of a tilting receptacle supported to be rocked by the weight of water flowing into it, one or more cups supported in said holder and connected with said receptacle to be raised and lowered by its movement, and a shield 25 extending over each cup.
